S. A. CRONE.

DOOR FOR GRAIN CARS AND LOCKING DEVICE THEREFOR.

(Application filed Nov. 9, 1901.)

(No Model.)

Fig. 1.

UNITED STATES PATENT OFFICE.

SETH A. CRONE, OF NEW YORK, N. Y.

DOOR FOR GRAIN-CARS AND LOCKING DEVICE THEREFOR.

SPECIFICATION forming part of Letters Patent No. 694,462, dated March 4, 1902.

Application filed November 9, 1901. Serial No. 81,649. (No model.)

To all whom it may concern:

Be it known that I, SETH A. CRONE, a citizen of the United States, and a resident of New York, in the county of New York and State of New York, have invented certain new and useful Improvements in Doors for Grain-Cars and Locking Devices Therefor, of which the following is a specification.

The invention relates to improvements in doors for grain-cars and locking devices therefor; and consists in the novel features, arrangements, and combinations of parts hereinafter described, and particularly pointed out in the claims.

15 The object of the invention is to provide more efficient, durable, and convenient means for hinging and locking the lower hinged panel found in grain-car doors and used as a means for discharging a part of the grain 20 from the car preparatory to the door as a whole being moved upward and then swung inward and secured at its lower end to the top of the car.

25 Grain-car doors possessing a hinged panel for the purpose referred to are old; but very great difficulty has been experienced in providing adequate and convenient means for enabling the hinged panel to be securely locked and to withstand the great pressure exerted 30 against it by the grain within the car, it being desirable and necessary that the hinged panel successfully withstand the pressure of the grain and be capable of being properly locked in closed position by means which 35 shall be durable, inexpensive, and capable of convenient operation.

The invention and satisfactory means for carrying the same into effect will be understood from the detailed description hereinafter presented, reference being had to the accompanying drawings, in which—

Figure 1 is a side elevation of a portion of a grain-car door constructed in accordance with and embodying the invention. Fig. 2 is 45 an enlarged vertical section, partly broken away, of same on the dotted line 22 of Fig. 1. Fig. 3 is an enlarged side elevation of a portion of same, this view being presented more particularly for the purpose of illustrating 50 one of the hinges for the panel of the door. Fig. 4 is a vertical section of same on the dotted line 44 of Fig. 3. Fig. 5 is a detached

enlarged front view of a plate to be carried by the hinged panel and constituting a part of the locking devices. Fig. 6 is a rear view 55 of same. Fig. 7 is a bottom edge view of same. Fig. 8 is a detached front view, partly broken away, of a lever forming a part of the locking devices. Fig. 9 is a view taken from the inner side of same, and Fig. 10 is a top 60 edge view of same.

In the drawings, 15 designates the grain-car door, and 16 the hinged panel of same, the door 15 and panel 16 being, apart from the features hereinafter referred to, of usual or 65 suitable construction. The door 15 is employed to confine the grain within the car, and at the proper time the panel 16 is opened outwardly to permit as much of the grain as possible to escape, after which under usual conditions the door 15 is moved vertically upward between its side frames (indicated by dotted lines in Fig. 1) until its upper end reaches the upper ends of said side frames, whereupon the door 15 is turned inward and 70 the lower end of the door is secured to suitable fastening devices suspended from the roof of the car. After the doors 15 of a car have been thus secured the grain remaining 75 in the car is manually discharged therefrom. 80

The present invention has to do with the means for hinging and locking the panel 16, and in accordance with my invention I provide locking means which engage the lower central portion of the panel 16 and hinge said 85 panel at the points below the upper edge of same.

The panel 16 is provided at its upper corners with plates 17, carrying the pins 18, which project beyond the vertical end edges 90 of the panel 16 and enter the sleeves 19, formed in the plates 20, secured to the door 15. The pins 18, coöperating with the sleeves 19, constitute the hinges for the door 16, and said pins and sleeves are disposed below the 95 upper edge of the door, so as not only to afford hinges, but means for aiding in preventing the grain within the car from forcing the ends of the panel 16 outward from between their inclosing surfaces. The sleeves 19 are 100 somewhat elongated in a vertical direction, as more clearly shown in Figs. 3 and 4; but the inner surfaces of said sleeves will at all times engage the outer surfaces of the pins

18, so as to be capable of binding the ends of the panel 16 in their normal position and aid the same in resisting the pressure of the grain within the car. The purpose of providing 5 the elongation in the sleeves 19 is to enable said pins 18 to move slightly upward in the sleeves 19. When due to any shrinkage in the door the latter may while being locked in closed position be moved slightly upward.

10 The door 15 is, above the upper edge of the panel 16, provided with the plate 21, which extends downward below the upper edge of the panel 16 and serves as a brace for the latter when said panel is in closed position, as 15 shown in Fig. 2. The plate 21 will aid in preventing the panel 16 from being bulged outward at its upper edge under the pressure of the grain within the car, and said plate 21 will not interfere with the operation of the 20 panel 16, since the pins 18 of the hinges are below the upper edge of the panel 16 and enable said edge to turn inward from the plate 21 when the panel 16 is opened. When the panel 16 is moved to its closed position, its 25 upper edge will move outward against the lower projecting portion of the plate 21, and said plate will at such time coöperate with the hinges and the locking devices in enabling the said panel to successfully resist 30 the pressure of the grain within the car.

Upon the lower central portion of the outer face of the panel 16 is firmly secured the plate 22, which is provided with the vertical slot 23 and inner recess 24 for the bolt or dog 25, the latter being vertically disposed and extending outward beyond the face of the plate 22 to a sufficient extent to enable its lower edge to engage the teeth 26 of the lever 27, the latter being pivotally secured to the door 35 15 below the aforesaid plate 22. The dog 25 at its inner end is in the form of a plate 28, confined within the recess 24 of the plate 22, said plate 28 serving to prevent the dog 25 from escaping from the plate 22 and also affording a means for guiding said dog. The dog 25 is also guided by the opposite vertical faces of the slot 23, along which are flanges 40 45 50 55 60 65 29 to strengthen said plate 22 and afford adequate guiding-surfaces for the dog 25. The lower edge of the dog 25 is beveled at one side, as shown in Fig. 5, so that it may be automatically raised by the contact therewith of the beveled sides of the teeth 26 of the lever 27 during the locking of the panel 16. At its lower edge the plate 22 is formed with the inclined or wedge surface 30, (clearly illustrated in Figs. 5 and 7,) whose highest portion is adjacent to the lower end of the vertical slot 23. The recess 24 in the plate 22 inclines outward 60 65 70 75 80 85 90 95 100 105 110 115 120 125 130 toward its lower portion, as denoted by the dotted lines in Fig. 2, and the purpose of this feature of the construction is to cause the dog 25 to remain at the lower end of the slot 23 when the door 15 is turned inward and secured at its lower end to the usual means suspended from the roof of the car, the door 15 at such time being at nearly a horizontal position,

and when the door is in this position the panel 16 will be on the same inclination, and the inclined surfaces of the recess 24 in the plate 22 will tend to keep the dog 25 at the lower end of the slot 23, it being desirable when the door 15 is thus secured at its lower end from the roof of the car that the panel 16 shall remain locked in closed position; otherwise said panel might turn downward and constitute an obstruction.

The lever 27 is mounted upon a sleeve 31, through which passes the securing and sustaining bolt 32 and which is integral with the plate 33, securely fastened to the door 15, below the panel 16 thereof and in line with the plate 22, fastened upon said panel. The lever 27 is formed with the handle 34 at one end, and at its other end said lever is formed with the segment 35, having the teeth 26, and at its inner side being beveled or of wedge outline, as denoted at 36. The lever 27 is formed on its inner face with a hub 38, which passes upon the sleeve 31 and engages the plate 33. The teeth 26 of the segment 35 are beveled on one edge and straight on the other edge, as shown, and when the lever 27 is in position the beveled surface 36 thereof is adapted to be moved against the beveled surface 30 of the plate 22 during the movement downward of the handle 34 and the consequent movement upward of the teeth 26 below the dog 25. When the lever 27 is turned to a horizontal position, its straight edge 39 will lie just below the lower edge of the panel 16, and at such time the panel 16 may be turned to its open position. When, however, the panel 16 is in its closed position and it is desired to there lock the same, the lever 27 will be turned to its vertical position, this operation causing the wedge surfaces 36 and 30 to move against each other and force the panel 16 firmly to its closed position. When the lever 27 is turned to its vertical position, the teeth 26 will move against the lower end of the dog 25, and the dog 25 will ride over said teeth 26 until the panel 16 has been completely closed, when the dog 25 will engage the last tooth which passed beyond it and serve to lock the lever 27 in its then position, whereby the lower edge of the panel 16 will become securely bound and locked in its closed position, the dog 25 holding the lever 27 and the upper end of the lever 27 binding against the lower portion of the plate 22 and being prevented from springing outward by means of the retaining-bolt 32. When the grain-car door is new, the dog 25 in locking the panel 16 may engage the first tooth of the lever 27; but as the panel 16 becomes worn or warped or otherwise distorted the dog 25 will be enabled to engage the second or third or fourth one of the teeth 26, since under such conditions the lever 27 may be turned to a greater extent for the effectual locking of the panel 16. It is desired that the panel 16 shall be so securely locked that the jarring of the car shall not be enabled to effect the movement of the

lever 27 or dog 25, whether the grain-car door 15 is in its vertical or in its inoperative position, suspended from the ceiling of the car, and this result is accomplished with the employment of my present invention.

The panel 16 when closed is securely held at its ends by the pins 18 and sleeves 19, and at the center of its upper and lower edges, respectively, by the plate 21 and lever 27. 10
Should the panel 16 shrink or become worn or distorted, the wedge surfaces 30 36 will enable the lever 27 to force the said panel firmly inward within the outlines of its inclosing surfaces, and should this panel under this action be moved slightly upward (due to the inclined upper and lower edges of said panel and its inclosing surfaces) the pins 18 may pass upward within the sleeves 19, the latter being vertically elongated for this purpose.

20 What I claim as my invention, and desire to secure by Letters Patent, is—

1. The grain-car door having the panel 16, and the hinges for the ends of said panel, said hinges being set below the upper edge of the 25 panel and comprising the horizontal pins 18 on which said panel may turn, combined with a locking device for securing the central portion of the lower edge of said panel, and the plate 21 for bracing the central portion of the 30 upper edge of said panel; substantially as set forth.

2. The grain-car door having the panel 16 and an opening for and to receive said panel, the lower edges of said panel and said opening being beveled to effect at the proper time the upward movement of said panel within said opening, and the hinges for the ends of said panel, said hinges comprising the horizontal pins 18 on which said panel may turn 40 and the sleeves 19 receiving said pins and being elongated vertically to permit an upward movement of said panel during the firm closing of the latter, said pins 18 being set below the upper edge of said panel, combined with 45 means for locking said panel at its lower edge; substantially as set forth.

3. The grain-car door having the panel 16, combined with means for locking said panel in closed position, said means comprising the 50 slotted plate 22 containing in its slot the movable dog 25, and the pivoted lever having the toothed end to be engaged by said dog, said plate being secured upon said panel and said lever being pivotally secured to said door below said panel in position when the lever is turned in one direction for said toothed end to pass below said panel and when said lever is turned in the other direction for said toothed end to pass upward above the lower edge of 55 said panel and against the lower end of said dog, whereby said dog is enabled to engage said toothed end and said lever is enabled to lock said panel in closed position; substantially as set forth.

60 4. The grain-car door having the panel 16, combined with means for locking said panel in closed position, said means comprising the

plate 22 fastened to said panel and having the slot 23 and inner recess 24, the movable dog 25 within said slot and having the retaining- 70 plate 28 within said recess; and the lever having the toothed end to be engaged by said dog, said lever being pivotally secured to said door below said panel in position when the lever is turned in one direction for said toothed end to pass below said panel and when said lever is turned in the other direction for said toothed end to pass upward above the lower edge of said panel and against the lower end of said dog, whereby said dog is enabled to 75 engage said toothed end and said lever is enabled to lock said panel in closed position; substantially as set forth.

5. The grain-car door having the panel 16, combined with means for locking said panel in closed position, said means comprising the plate 22 fastened to said panel and having the slot 23 and downwardly and outwardly inclined inner recess 24, the movable dog 25 within said slot and having the retaining- 90 plate 28 within said recess and against the inclined surfaces thereof, and the lever having the toothed end to be engaged by said dog, said lever being pivotally secured to said door below said panel in position when the lever 95 is turned in one direction for said toothed end to pass below said panel and when said lever is turned in the other direction for said toothed end to pass upward above the lower edge of said panel and against the lower end 100 of said dog, whereby said dog is enabled to engage said toothed end and said lever is enabled to lock said panel in closed position; substantially as set forth.

6. The grain-car door having the panel 16, combined with means for locking said panel in closed position, said means comprising the plate 22 fastened to said panel and having the movable dog 25, and the lever 27 having at one end the teeth 26 to be engaged by said dog and provided on its inner face with the wedge-surface 36 to engage the outer face of said plate 22 for forcing said panel to closed position, said lever being pivotally secured to said door below said panel in position when the lever is turned in one direction for said toothed end to pass below said panel and when said lever is turned in the other direction for said toothed end to pass upward above the lower edge of said panel and against the lower end of said dog, whereby said dog is enabled to engage said toothed end and said lever is enabled to lock said panel in closed position; substantially as set forth.

7. The grain-car door having the panel 16, combined with means for locking said panel in closed position, said means comprising the plate 22 fastened to said panel and having the movable dog 25 and exposed wedge surface 30, and the pivoted lever 27 having at one end the teeth 26 to be engaged by said dog and provided on its inner face with the wedge surface 36 to engage the said wedge surface 30 for forcing said panel to closed position,

4
said lever being pivotally secured to said door below said panel in position when the lever is turned in one direction for said toothed end to pass below said panel and when said lever 5 is turned in the other direction for said toothed end to pass upward above the lower edge of said panel and against the lower end of said dog, whereby said dog is enabled to engage said toothed end and said lever is enabled to lock said panel in closed position; substantially as set forth.

8. The grain-car door having the panel 16 therein, and the hinges for the ends of said panel, said hinges comprising the horizontal 15 pins 18 and sleeves therefor, said pins being set below the upper edge of the panel and

serving as pivots for the same and also as means for bracing the ends of said panel against the pressure of the grain, combined with means for bracing the upper edges of 20 said panel when the latter is in closed position, and a locking device for securing the lower edge of said panel; substantially as set forth.

Signed at New York, in the county of New 25 York and State of New York, this 8th day of November, A. D. 1901.
